UNITED STATES PATENT OFFICE.

JOSEPH A. STEINMETZ, OF PHILADELPHIA, PENNSYLVANIA.

AEROMARINE TORPEDO.

1,223,212.

Specification of Letters Patent. Patented Apr. 17, 1917.

Application filed March 7, 1916. Serial No. 82,866.

To all whom it may concern:

Be it known that I, JOSEPH A. STEINMETZ, a citizen of the United States, residing at Philadelphia, in the county of Philadelphia and State of Pennsylvania, have invented 5 certain new and useful Improvements in Aeromarine Torpedoes, of which the following is a specification, reference being had therein to the accompanying drawings.

10 The object of this invention is to provide simple and inexpensive means whereby aeroplanes, or hydro-aeroplanes, moving at high speed may attack ships with contact torpedoes which are not self-propelling.

15 In the accompanying diagrammatic drawings,

Figure 1 shows my devices as they may be used in attacking a ship.

Fig. 2 is a longitudinal detail section of 20 devices whereby an aeroplane causes a torpedo to be driven through the water.

Fig. 3 shows a hydro-aeroplane towing directly a boat from which a torpedo is suspended.

25 Fig. 4 shows the same devices with the middle portion of the towline resting upon an attacked vessel.

Fig. 5 illustrates the action of the devices in attacking a vessel protected by nets.

30 In these views, A represents any vessel to be attacked, B a hydro-aeroplane, C a small pontoon-like boat from which a contact bomb or torpedo D is suspended by cables E near its ends, respectively. The 35 boat C is preferably a shell provided with a propeller F upon a shaft G which is rotated through gearing H by a suitable line or cable I, preferably a piano wire or the like, wound upon a large drum J and passing out of the shell through a suitable eye K, then through an eye at the end of a lever L, and thence to the hydro-aeroplane B. The lever L is centrally pivoted at M and when its outer end is swung downward 40 by the descent of the wire, the lower or inner end of the lever swings against the drum J locking it against rotation.

If the hydro-aeroplane be moving near the water or upon the water as indicated in 45 Fig. 3, the drum J is locked and the boat and bomb may be towed for any distance at any speed without material rotation of the drum. It is thus a simple matter to carry the torpedo, by means of the aeroplane, anywhere on the sea at high speed if

desired, even though the boat and torpedo are too large to be carried in the air by the flying craft. When the apparatus approaches a vessel to be attacked, the hydro-aeroplane rises, as indicated in Fig. 1, and passes far above such vessel. In such case the swinging of the lever to the position of full lines in Fig. 2, releases the drum and the pull of the rapidly flying machine above unwinds the wire from the drum, rapidly 55 rotating the latter and causing the propeller to force the pontoon to advance rapidly while it is guided by the flying machine. Whenever the flying machine moving at its necessarily high speed withdraws the wire 70 from the drum the latter is rotated with great rapidity and the boat is advanced by the pull of the wire and also by the high speed of the propeller, and should the wire be divided the boat and torpedo will still 75 advance quickly through a considerable distance and may probably insure the destruction of the attacked vessel. Should the pontoon be suddenly stopped by a guard net N or the like, the momentum of the torpedo 80 will carry it forward below the net and cause it to strike the side of the vessel, the cables E being longer than the usual depth of a net. The wire being small, a very great length may be wound on the drum, yet at 85 any time the supply may be conserved if the flying boat descends either when mere transportation is desired, as indicated in Fig. 3, or when the attacking hydro-aeroplane has passed to some distance beyond 90 the attacked vessel as shown in Fig. 4. If the wire has fallen across the attacked vessel as shown, rapid advance of the hydro-aeroplane upon the water will quickly draw the boat against the vessel. If the wire 95 has not fallen upon the vessel the flying machine may move in any direction upon the water without causing further unwinding of the wire, towing the torpedo, if necessary, to some distance and then itself returning to the same side of the attacked vessel and repeating the proceeding described. If desired, the wire may be cut at any time and the boat or pontoon may be picked up at any later time, for another attack, or otherwise.

Obviously, the flying machine may if desired cause rapid advance of the torpedo toward any object by simply rising and moving from side to side to direct the tor- 110

pedo, and indeed the air craft may cause this advance while itself moving in the opposite direction.

The rate at which the wire is drawn from the drum is controlled by the aviator, and thus both the speed and direction of the torpedo are under his control. It is quite possible by the use of large vessels or otherwise, to provide several boat-supported torpedoes in the same vicinity, and a flying boat may select any of these, or several in succession, to be engaged and used in attack, as described.

It is to be noted that the torpedo is of the simplest character, made quickly and at such low cost that its loss is not usually, for any reason, serious.

What I claim is:

1. The combination with a small boat, of a torpedo suspended from the boat, a propeller supported by the boat, a distant flying machine, a cable connecting the boat to the flying machine to allow the latter to tow the boat and torpedo, and means whereby the cable may by tractive force of the flying machine actuate the propeller.

2. In apparatus of the class described, the combination with a flying machine provided with a depending cable, of a small boat, a propeller carried by the boat and driven by force exerted through the cable by the flying

machine, means whereby the aviator may at will cause said force to drive the propeller or to advance the boat by simple towing action, and a contact torpedo suspended from the boat.

3. In apparatus of the class described, the combination with a small boat provided with a propeller, of a drum arranged to impart its own rotation to the propeller shaft, a cable wound upon the drum, and a contact torpedo suspended from the boat, whereby traction on the cable rotates the propeller and advances the boat and torpedo.

4. The combination with a hydro-aeroplane, of a small boat and a contact torpedo suspended therefrom, of a propeller for the boat, a drum arranged to impart its own rotation to the propeller shaft, a cable wound upon the drum and attached to the hydro-aeroplane, and means whereby variation in elevation of the hydro-aeroplane locks and releases the drum, thus causing the cable to act as a simple towline or to drive the propeller.

In testimony whereof I affix my signature in presence of two witnesses.

JOSEPH A. STEINMETZ.
